(57) **CLAIM**

The ornamental design for a weighted exercise glove, as shown and described.

DESCRIPTION

FIG. 1 is a perspective view of a weighted exercise glove showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof with a wrapped wrist band.

The short dashed broken lines shown within the bounds of the weighted exercise glove depict claimed stitching. The long dashed broken line outline of the partial human hand in FIG. 8 assists in illustrating how the weighted exercise glove may appear when in a position of use, but forms no part of the claimed design.
